COAT

Jerome Giuseffi, Cincinnati, Ohio, assignor to
 The Goodall Worsted Company, Sanford,
 Maine, a corporation of Maine

Application July 17, 1943, Serial No. 495,108

5 Claims. (Cl. 2—93)

This invention relates to a coat, particularly of the jacket type and provided with means for securing an undisturbed and undistorted hang or drape of the body of the coat despite movement of the arms.

A further object of the invention is to provide a coat of the kind described in which the means employed in accordance with the invention do not modify the desired appearance of the coat as a whole.

Another object is to provide a coat of this kind in which the construction is simple and efficient, and the additional material utilized negligible.

These and other objects are attained by the means described herein and illustrated in the accompanying drawing, in which:

Fig. 1 is a perspective view of a coat of this invention in wearing position, looking toward the back and one side of the coat, the arm being shown raised and partially broken away.

Fig. 2 is a plan view showing the coat of this invention turned inside out and doubled upon itself for disclosing the construction of this invention adjacent the armhole.

Fig. 3 is an enlarged cross-sectional view on the line 3—3 of Fig. 2.

Fig. 4 is a plan view of a piece of material cut in accordance with the present invention, and forming the under or inner side of one of the sleeves.

Fig. 5 is a plan view of the upper portions of the piece seen in Fig. 4, with the top extension doubled upon itself.

Fig. 6 is a cross-sectional view on line 6—6 of Fig. 5.

One of the difficulties long apparent in the construction of a coat or other sleeved garment has been the lifting and distortion of the body of the garment when the arms are raised or similarly moved. The problem has not been satisfactorily solved heretofore, although attempts have been made to do so, such as by the provision of plaits or the like extending rearwardly of the shoulder. Such constructions, however, have not been practicable, and moreover, have so changed the appearance of the garment as to be undesirable from this viewpoint also.

The present invention overcomes these and similar difficulties by providing briefly for an extension attached to the underside of the sleeve at the top, and so connected to the body of the coat below the armhole that, upon raising of the arm, the extension acts in the manner of a hinge element, moving outwardly of the body of the coat in accordance with the requirements of the

arm movement, but leaving the body of the coat undisturbed.

In greater detail, and with reference to the drawing, the invention contemplates a coat of any suitable general construction, the one shown herein being of the skeleton lined type and comprising the body 10, collar 11, shoulder 12 and sleeve 13.

The sleeve of the present construction is formed of an upper or outer piece 14, Fig. 1, and a lower or underpiece 15, Figs. 1 and 4. The piece 14 may be of the usual construction, but the piece 15, in accordance with the present invention, is formed at the top with an extension 16, Fig. 4, of such outline as when folded upon itself, along a diagonal line 17, assumes a generally triangular form such as seen in Fig. 5, at which time said extension comprises an outer ply 18 and an inner ply 19.

20 The sleeve, provided with an under piece of the form just described, is applied to the armhole portion of the body 10 by attaching the outer piece 14 to the shoulder portions 12 as at 20, Fig. 3. The underarm piece 15, however, is attached to 25 the coat body as indicated in Figs. 1 and 2, with the underlying plies 18 and 19 of the extension 16 disposed against the outer surface of the coat body, under the armhole. The parts are held in this position by stitching 21, which passes through 30 the lateral edge portions of both of the plies 18 and 19. The inner ply 19, as seen in Fig. 5, is cut with an arcuate upper edge 22 so as to conform with the lower portions of the armhole and with which portions said arcuate edge 22 is attached as at 23, Fig. 3. Suitable binding 24 covers the exposed edges at the armhole of the coat.

The outer ply 18 is not attached to the armhole portions of the coat as is the inner ply 19. 40 but rather projects above the lower portions of the armhole as seen at 25, in Figs. 2 and 3, when the sleeve or arm is in normal down-hanging position.

Since the outer ply 18 of the extension 16 has 45 its upper portions free relative to the body of the coat, it functions as a kind of hinge member providing a surplus which moves outwardly of the body of the coat when the arm is raised, obviating the usual simultaneous lifting and distortion of the body of the coat, which therefore maintains its desired draped appearance.

What is claimed is:

1. A coat comprising an armhole and provided with a sleeve formed with an under-arm extension at the top of the sleeve, the extension being

folded downwardly from the upper end of the sleeve to form an outer ply and then upwardly upon itself below the armhole to form an inner ply disposed adjacent and secured along its lateral edges to the body of the coat and along its top edge to the lower portion of the armhole, said outer ply having its edges attached to the body of the coat, the top portion of the outer ply normally projecting above the lower part of the armhole and free relative thereto whereby upon raising of the arm said outer ply hinges outwardly relative to the body of the coat for obviating lifting and distortion of the latter.

2. A coat having an armhole and comprising a sleeve formed at the top with an under-arm extension doubled downwardly on itself to form an outer ply adjacent the sleeve and an inner ply adjacent the body of the coat, the inner ply being attached flat against the body of the coat with its upper edge secured to the lower part of the armhole, the outer ply having its edges attached to the body of the coat and the top portions projecting above the lower part of the armhole and free relative thereto whereby upon raising of the arm said outer ply hinges outwardly relative to the body of the coat for obviating lifting and distortion of the latter.

3. A coat having an armhole and comprising a sleeve formed at the top with an under-arm ex-

10 tension doubled downwardly on itself to form an outer ply adjacent the sleeve and an under ply adjacent the body of the coat, the under ply being attached flat against the body of the coat with its upper edge secured to the lower part of the armhole, the outer ply having its edges attached to the body of the coat and the top portions projecting above the lower part of the armhole and attached thereto at opposite sides only forming a surplus adapted upon lifting of the arm to hinge outwardly for obviating lifting and distortion of the body of the coat.

15 4. A coat formed with an armhole, and a sleeve formed with an under-arm extension having its edges attached to the body of the coat below the armhole, the upper part of the extension projecting above the lower edge portions of the armhole and free relative thereto for providing a surplus for obviating lifting and distortion of the coat body upon raising of the arm.

20 5. A coat formed with an armhole, and a sleeve formed with an under-arm extension having its edges attached to the body of the coat below the armhole, the upper part of the extension projecting above the lower edge portions of the armhole and attached thereto at opposite sides only forming a surplus for obviating lifting and distortion of the coat body upon raising of the arm.

JEROME GIUSEFFI.
